MIXING AND HOMOGENIZING APPARATUS

William R. Kinnaird, Riverside, Ill., assignor to
Universal Oil Products Company, Chicago, Ill.,
a corporation of Delaware

Application February 25, 1950, Serial No. 146,273

1 Claim. (Cl. 259—8)

This invention relates to improved apparatus suitable for the mixing of different fluid streams, and more particularly to a mixer which is constructed in a manner to be operated continuously to effect the thorough mixing of miscible liquids, or alternately, the dispersion or homogenization of immiscible fluid mediums.

It is an object of the present invention to provide a mixer of relatively simple construction which combines flow mixing, jet stream or spray mixing, and paddle mixing to effect efficient and thorough mixing of different fluid streams.

It is also an object of the present invention to provide a mixing apparatus which incorporates therewith means for effecting a shearing action on a fluid stream and a resulting homogenization or emulsification of immiscible fluid streams, or alternatively the dispersion of finely divided solids in a liquid medium to provide a quasi-homogeneous product.

In a broad aspect, the present apparatus for mixing different fluid streams comprises in combination, a cylindrical housing, a hollow shaft held rotatably within and extending axially through said housing, with one end of the hollow shaft extending exteriorly of the housing, fluid inlets connecting to the exterior end of the rotating hollow shaft, a plurality of sets of fluid orifices from the hollow shaft at spaced distances along the latter within the housing, each of the orifices of each set being constructed and positioned angularly with respect to the hollow shaft in a manner causing the impingement of a plurality of jet-like streams against an adjacent dish shaped baffle plate, there being one baffle plate for each of the sets of orifices and each plate having a diameter substantially smaller than that of the interior diameter of the cylindrical housing, adjacent sets of orifices being constructed and positioned at divergent angles with respect to the hollow shaft and the accompanying dish shaped baffles are positioned in opposition to one another, whereby the resulting fluid streams sprayed from the sets of orifices and subsequently from the periphery of each of the dish shaped baffles provide a plurality of crossing streams, a mixed fluid outlet from the housing, and power driven means connecting with the hollow shaft in a manner to rotate the latter within the cylindrical housing.

A plurality of paddles or propeller like blades may also be used to advantage within the mixer, the blades extending radially from the hollow shaft to within a short distance of the interior wall of the cylindrical housing and provide

thereby additional mixing and turbulence within the housing.

The housing and the hollow shaft extending longitudinally therethrough may be positioned horizontally or vertically, depending upon the particular type of fluid mediums to be mixed. In any case, a single rotating hollow shaft is utilized, with a suitable motor or driving means attaching to the exterior end of the shaft so as to continuously rotate the latter within the cylindrical housing. The apparatus thus provides a relatively simple form of construction, with only one member being rotated mechanically. There is utilized to advantage a confined fluid passageway, orifices, baffles, centrifugal rotation, and mixing blades to combine many types of mixing and provide a very efficient overall means of effecting the mixing of either miscible or immiscible fluid streams.

20 In a modified embodiment, a cone-shaped member is attached to the end of the rotating shaft and is positioned in close proximity to a matching cone-shaped head or end member of the housing so as to develop a shearing action 25 on the fluid stream, resulting from the relative rotation of one surface with respect to another, to in turn be effective in the emulsifying or homogenizing of immiscible streams or mixtures. In this embodiment, the cylindrical housing is preferably placed in a vertical position and the homogenizing cone is attached to the rotating hollow shaft at the lower end of the unit. The unmixed fluid streams being introduced to the interior of the hollow shaft at the 30 upper end of the mixing apparatus, become mixed in a series of recrossing sprayed streams during their downward passage through the mixer, and subsequently homogenized by the rotating cone member and closely placed cone-shaped end of the housing to permit the withdrawal of a homogenized or quasi-homogeneous product stream from the center of the lower 35 end of the unit.

40 The construction and operation of the improved mixer will be more apparent upon reference to the accompanying drawing and the following description thereof, also, additional uses and advantages will be noted in connection with the description of the drawing.

45 Referring now to the drawing, there is shown an elevational view, partially in section, of one embodiment of the improved mixing apparatus of this invention. This particular embodiment is indicated as being vertically disposed, with a cylindrical housing 1, held on a base 23, and a ver-

tically positioned rotatable hollow shaft 2. The shaft 2 is held in axial alignment within the housing 1 by means of a bearing 3 and a packing gland 4, maintained within the upper head or closure member 5, and by means of a lower internal bearing 6 which is in turn supported by suitable spokes or web members 7 that connect with the inside of the cylindrical housing 1. Preferably the lower bearing 6 is of a thrust type roller bearing suitable to accommodate the load 10 of the hollow shaft and its attachments.

A suitable seal 8 is utilized at the top of the rotating hollow shaft in order to connect therewith a stationary conduit 9 and fluid inlets 10 and 11. Also, a suitable sheave, or gearing 12, or the like, is attached to the upper end of the hollow shaft externally of the cylindrical housing, in order that a motor or other power driven means may connect with the shaft and rotate the latter within the housing.

The fluid streams which are to be mixed, and being introduced by way of inlets 10 and 11, and through the shaft seal 8 into the interior of the hollow shaft 2, pass in a mixed fluid stream continuously downwardly through the entire shaft and outwardly through a plurality of sets of orifices, indicated by the numerals 13 and 14. As will be noted upon reference to the drawing, the various orifices 13 are drilled or otherwise placed through the wall of the hollow shaft 2 so that jet like streams of fluid pass upwardly and outwardly to impinge against the inner face of a dish-shaped baffle 15, while the jet like streams from the orifices 14 are projected downwardly and outwardly from the hollow shaft 2, to impinge against the dish-shaped baffles 16. The baffle plates 15 and 16 are circular and in each case dish-shaped or concave with respect to the impinging jet streams, so that the fluid streams subsequently leave the periphery of each of the dished baffle plates in a thin sheet-like stream or continuous film. The sets of orifices 13 and 14 and the accompanying baffles 15 and 16, for each of the respective sets of orifices, are spaced longitudinally along the hollow shaft 2, such that the resulting sheet-like fluid streams from the periphery of each of the baffles will cross with another, within the cylindrical housing 2.

The jet streams from the orifices and the resulting crossing of sprayed streams from the peripheries of the baffle plates 15 and 16 takes place in a continuous manner and during the continuous rotation of the hollow shaft and the attached baffles, so that there is a combination of methods of mixing. Flow mixing through the inside of the hollow shaft 2 and the orifices 13 and 14, with spray mixing resulting from the impingement of the jet orifices against the accompanying baffle plates and from the crossing of the streams after the fluid is allowed to flow from the periphery of the individual baffles. It is to be noted, that the sets of orifices, which are adjacent one another, are positioned or constructed in a manner to cause diverging jet streams of fluid, and the adjacent baffles 15 and 16 oppose one another, to provide a plurality of pairs of crossing streams or films of fluid and thus effect a high degree of mixing within the housing. Also, in a vertically disposed embodiment of the apparatus, as shown in the drawing, there will be a considerable amount of spray mixing from the falling droplets or films of fluid which results from the upper of the crossing stream contacts and tend to rain down through the length of the entire mixer.

The present embodiment has a plurality of blades or curved propeller-like blades 17 which project radially from the hollow shaft 2. Such blades are effective in the breaking up and further mixing of such liquid as may be raining or flowing downwardly through the housing. Alternatively, where the mixing chamber is lying in a horizontal position, the blades are effective in stirring and mixing the liquid which accumulates in the lower portion of the unit. While the present drawing indicates the curved blades in sets of 4, it is not intended to limit the mixer to any particular number of blades, or to any particular shape. The spacing of the sets of orifices and of the baffles 15 and 16, as well as the diameter of the latter, is correlated with respect to the speed of rotation of the hollow shaft, in order that the resulting films of fluid which are centrifuged from the outer periphery of each of the baffles is permitted to cross with and mix with the adjacent set of orifices and baffle plates.

The lower end of the present embodiment is provided with a cone-shaped member 18 which is attached to the lower end of the hollow shaft 2, such that it is rotated therewith. The member 18 in this particular mixer also serves to cap or block the fluid flow from the end of the hollow shaft 2 such that all of the fluid medium is passed outwardly through the plurality of orifices 13 and 14. The cone-shaped member 18 provides a conical surface of revolution which is in close proximity to a cone-shaped head 19 at the lower end of the cylindrical housing and thus provides in turn a relatively thin conically shaped passage-way for the fluid stream to be passed through prior to reaching the outlet 20 at the lower end of the chamber. The rotating surface provided by the surface of the cone member 18 develops a shearing action on the fluids to produce a fine dispersion or emulsion of non-miscible fluids, or alternatively, to provide a homogeneous or quasi-homogeneous product, depending upon the type of streams being mixed.

Adjustment means are preferably provided to regulate the spacing between the cone member 18 and the lower head 19 and in turn permit adjustability in the homogenizing action on the fluid stream passing from the mixing section to the outlet 20. The present embodiment provides a plurality of bolts or cap screws 21 and slotted holes 22 in the head 19 so that the latter can be moved up and down with respect to the cone member 18 and regulate the spacing therebetween, however, other more readily operated mechanical means may be utilized to advantage to provide the desired adjustment.

It is not intended to limit the present mixing and homogenizing apparatus to any one use, for obviously, it may be utilized to advantage in many types of contacting and mixing operations. For example, with petroleums, it may be utilized to effect the dispersion between a gasoline and caustic stream in a treating process, or alternatively, with an acid to provide a catalytic conversion. The apparatus may also be used to advantage to mix a liquid and solid, such as a finely divided pigment in a suitable vehicle, as in the manufacture of paint, or the mixture of other finely divided solid material in the formation of slurry streams.

Particularly advantageous features of the improved unit, reside in the simple construction using a single rotating shaft, so that the power or driving means may be connected with the shaft externally of the mixing housing or cham-

ber 1, and there is no necessity to attach or connect driving or rotating means to an internal portion of the unit. The hollow shaft also permits the introduction of the streams to be mixed, into the center of the chamber and throughout the entire length of the unit in a simultaneous manner to thus maintain uniformity of mixing over long sustained periods of operation.

As briefly pointed out hereinbefore, a plurality of the well known methods of mixing are combined in an efficient and advantageous manner in this single apparatus. To recapitulate, turbulent flow mixing is obtained within the internal portion of the rotating shaft 2, by virtue of the confined flow channel and the continuous rotation of the shaft itself. Jet or orifice mixing is obtained by means of the continuous flow through all of the plurality of sets of orifices 13 and 14 that spray against the dished baffle plates 15 and 16, each baffle being concave to their respective set of orifices. The impinging jet streams in turn tend to diffuse and mix upon the surface of each of the baffles and form a continuous sheet-like film of fluid which is centrifuged outwardly and away from the outer periphery of each of the baffle plates, by virtue of the continuous flow and the continuous rotation of the baffles with the hollow shaft 2. In still another step, there is a cross flow mixing, resulting from the sprayed streams from the peripheries of baffles 15 and 16. The plurality of propeller-like blades 17 effect still further mixing and turbulence by virtue of their continuous rotating motion throughout spaced portions of the housing.

In still another step, an homogenizing cone, such as 18, may be combined with the mixing section of the unit to exert a shearing action on the fluid stream and effect a desired homogenizing or emulsification of immiscible fluid streams.

The power requirements for the motor or other driving means attached to the rotating shaft 2 will of course vary in accordance with the type of fluid streams which are being introduced into the mixer, however, it may be pointed out that

the improved construction and arrangement is such that the power requirements are substantially low as compared with a mixer which has blades or paddles acting directly within a retained body of liquid. In other words, the present paddles act on sprayed streams or raining droplets of liquid resulting from the cross stream contact.

I claim as my invention:

10 A fluid mixing apparatus comprising a vertically positioned cylindrical housing, a hollow shaft rotatably mounted in and extending axially through said housing, means for introducing fluids to said shaft, means for rotating the shaft, a plurality of pairs of dish-shaped baffles of approximately equal diameters mounted on said shaft in opposition to each other and having their peripheries vertically spaced a substantial distance apart, whereby fluid films discharging from 15 the peripheries of the respective baffles cross each other within the housing, a set of orifices in said shaft a short distance below the upper baffle of each of said pairs and inclined upwardly toward the last-named baffle, a second set of orifices in 20 said shaft a short distance above the lower baffle of each of said pairs and inclined downwardly toward said lower baffle, a radially extending mixing blade on said shaft between adjacent pairs of the baffles, and means for removing mixed 25 fluids from said housing.
